(Cl. D93—3)

FIG. 1.

FIG. 2.

FIG.3.

FIG.5.

FIG.4.

Figure 1 is a view in perspective of a motor hand saw showing my new design;

Figure 2 is a side elevational view of the motor hand saw;

Figure 3 is a front elevational view of the motor hand saw;

Figure 4 is a side elevational view of the motor hand saw at the opposite side from that shown in the elevational view of Figure 2; and

Figure 5 is a fragmentary rear elevational view showing the lower part of the motor hand saw.

The dominant features of my design reside in the portions shown in full lines.

I claim:

The ornamental design for the motor hand saw, as shown and described.
